OTTO J. DREWS, OF MILWAUKEE, WISCONSIN, ASSIGNOR OF ONE PER CENT TO IRMA C. THUERMANN, FORTY-NINE PER CENT TO WILFRED J. THUERMANN, AND ONE PER CENT TO IRMA DREWS, OF MILWAUKEE, WISCONSIN

GARTER FASTENER

Application filed March 16, 1932. Serial No. 599,149.

This invention appertains to garter supporters and more particularly to a stocking supporter embodying a novel grip or fastener for engaging the stocking, said grip being susceptible for general purposes, such as 5 grips for blankets on baby cribs, supporting sanitary napkins and for use in grasping hose incident to the knitting thereof.

In the ordinary type of suspension garters, the stocking grip or fastener embodies 10 a gripping head or stud insertable in the restricted neck portion of a metal loop or body plate. The stocking is gripped between the head or stud and the body plate. This type 15 of stocking fastener is open to many serious objections, especially when used in connection with ladies' silk stockings. First, the stud or head presents a projection, which is often visible through the outer garments and 20 this projection causes the wearer considerable discomfort, especially when in a sitting position and when the projection comes into contact with a hard object. Second, the head only exerts a pull on a few of the stocking 25 threads, which causes the stocking to tear or run and in some instances, the stocking will slip unless the stocking is bunched around the stud or head.

Efforts have been made to overcome these 30 difficulties, such as by padding the head. This has not reduced the objections, and, as a result, stocking manufacturers have gone to considerable expense to knit stockings in which the tops will stop or check runs.

35 It is, therefore, one of the primary objects of my invention to provide a garter supporter having a novel stocking grip which will effectively overcome the above mentioned difficulties and which will grip 40 the stocking and hold the same against slipping and which will lie flat against the leg in parallel relation to the stocking entirely eliminating all projecting heads and the like.

45 Another salient object of my invention is the provision of a stocking fastener which will engage a great number of the stocking threads, so as to distribute the pull of the threads over a large area, thereby preventing 50 the tearing of the stocking and the making

of runs therein, the pull on the stocking being parallel with the threads.

A further prime object of my invention is the provision of a stocking fastener embodying inner and outer metal loops or links 55 which are adapted to lie parallel with the stocking, the longer of the two links or loops being insertable through the other loop or link for gripping the stocking between the links or loops, the stocking being securely 60 held at both ends of the loops and in such a manner that the stronger the pull on the stocking and garter supporter, the tighter the links or loops will grip and hold the stocking. 65

A further object of my invention is the provision of a stocking fastener of the above type, in which the shorter link or loop has its end cross bars offset inward of the plane 70 of the longitudinal side bars, whereby the longer link or loop will lie substantially within the plane of the shorter loop or link, when the longer link is inserted through the shorter link or loop for engaging the stocking. 75

A still further object of my invention is to provide an improved stocking fastener of the above character, which will be durable and efficient in use, one that will be simple and easy to manufacture and one which can 80 be placed upon the market at an extremely low cost.

With these and other objects in view, the invention consists in the novel construction, arrangement and formation of parts, as will 85 be hereinafter more specifically described, claimed and illustrated in the accompanying drawing, in which:

Figure 1 is a front elevation of the outer part of the stocking fastener illustrating the 90 relatively short loop or link;

Figure 2 is a similar view illustrating the longer metal loop or link;

Figure 3 is a front elevation showing the two links associated together, with the 95 longer link inserted through the shorter link and lying on the outer face thereof;

Figure 4 is a front elevation illustrating a slightly modified form of the inner or 100 relatively short link or loop;

Figure 5 is an enlarged diagrammatic view, showing the fastener in use and illustrating one of the initial steps for inserting the longer loop or link through the outer 5 shorter link or loop for grasping the stocking; 10

Figure 6 is a view similar to Figure 5 showing the longer loop or link inserted entirely through the shorter link or loop 10 with the two loops or links in their stocking 15 engaging position; and,

Figure 7 is a side elevation illustrating a shorter link with the cross bars thereof offset below the plane of the connecting side 15 bars.

Referring to the drawing in detail, wherein similar reference characters designate corresponding parts throughout the several views, the letter A generally indicates 20 my improved fastener for the suspension stocking supporter or garter. The fastener A includes an upper loop or bail 10 preferably formed from wire or similar material to which is connected in the ordinary manner, the elastic (not shown) of the garter. This bail or loop 10 has secured to its 25 lower cross bar, the relatively wide supporting fabric or tape 11. This fabric strip 11 can be formed from any desired material 30 possessing the necessary strength, such as tape above mentioned, elastic or the like. The lower end of the fabric strip 11 is folded about the upper cross bar 12 of the outer loop or link 13 which forms an 35 important part of my fastener. This outer loop or link 13 is formed from rounded wire or other stock of the desired gauge and includes the connecting parallel side bars 14 which connects the end cross bars 12 and 40 15 together. These end cross bars 12 and 15 are preferably offset below the plane of the side bars 14 as can be clearly seen by referring to Figure 7 of the drawing. The other part of my improved fastener comprises 45 an inner link or loop 16 which is likewise formed from round wire or other metal stock. This inner loop or link 16 includes the longitudinally extending side bars 17 and the end cross bars 18 and 19. This 50 inner link or loop is of a less width than the loop or link 13, but is formed longer than said loop or link 13, for a purpose, which will be later described and set forth.

Secured to the upper cross bar 18 of the 55 inner long link or loop 16 is a length of tape or similar supporting fabric 20 which is sewed or otherwise secured to the inner face of the fabric strip 11. By referring to Figures 3, 5 and 6, it will be noted that normally the inner link or loop 16 extends below the outer link or loop 13 and the tape 20 allows sufficient play to permit the insertion of the long inner link 16 through the outer short link or loop 13. In Figure 3, I have 60 illustrated the inner long link inserted

through the outer short link and lying on the outer face thereof.

In use of my improved stocking fastener, the short link 13 is placed on the outer face of the stocking (indicated by the reference character S in Figures 5 and 6) and the long link 16 is placed on the inner face of the stocking. The forward edge of the long link or loop 16 is now inserted through the short link or loop 13, carrying the stocking therewith. After the upper cross bar 18 of the long link 16 rides past the cross bar 12 of the short link or loop 13, the link 16 is swung outwardly and through the link 13 and is slid upwardly over the cross bar 12. 70 This position is shown in Figure 6 of the drawing and stocking will be normally held both at the lower and top ends of the links. In view of the offset cross bars 12 and 15 of the short link 13, the long link 16 will 75 lie substantially within the plane of the side bars 14 of the link or loop 13, and thus prevent twisting or turning of the long link 16. This provides a flat construction which 80 will not cause the wearer of the fastener 85 any discomfort.

The fastener is of such a character that the same will engage the stocking throughout its entire width and a large number of threads, from ten to fifteen will be engaged 95 by the fastener. This distributes the pull on the stocking and effectively prevents the tearing or the forming of runs in the stocking.

Obviously, minor changes in details can 100 be made and in Figure 4 I have illustrated one modification. In this form of the invention, the short link or loop can be formed on the lower end of a metal supporting frame 21, which takes the place of the fabric 105 strip 11. The metal frame 21 can be joined to the elastic receiving loop 22 by the use of a metal sleeve or the like 23. In this construction, the supporting tape 20 for the long loop 16 can be secured about the sleeve 110 23. Without departing from the spirit of my invention a flat plate of any suitable material could be substituted for the long link 16.

The device is extremely flexible and will 115 move with the body of the wearer and when the same is associated with the stocking, no metal parts can or will touch the body of the wearer.

Thus, the device lies flat and parallel with 120 the stocking and grips a maximum number of threads and exerts a straight pull thereon.

From the foregoing description, it can be seen that I have provided a novel stocking fastener of exceptionally simple and durable 125 construction, which consists of a minimum number of parts and which can be manufactured and placed on the market at a low cost.

While I have referred to the fastener as 130

being particularly adapted for use as a stocking supporter, it is to be understood that the same can be used for any purpose where a fabric grip is needed. Thus the 5 same can be effectively used for gripping blankets to hold the same on cribs and for holding hose incident to the knitting thereof.

Owing to the ease of manipulating the 10 clips and their positive grip and flat character, the clips are especially useful for holding sanitary napkins in position and the same entirely eliminate the use of safety pins and the dangers contingent therewith.

15 I claim:

1. In a stocking supporter, a suspended rectangular shaped ring formed of round wire stock and a second rectangular shaped ring formed of round wire stock loosely associated with the first ring and having a less width than said first ring and a greater length, said second ring being insertable through the first ring for gripping a stocking between said rings.

25 2. In a stocking supporter, a rectangular suspended ring including parallel side bars and connecting end bars, said end bars being offset inward of the plane of the side bars, a second rectangular shaped ring movable 30 relative to the first ring and of a less width than said first ring and a greater length, said second ring including parallel side bars and connecting cross bars and insertable through the first ring for gripping a stocking 35 between said rings, the second ring when inserted through the first ring being adapted to rest upon the end cross bars of the first ring and lying substantially within the plane of the side bars of the first ring, and 40 means connecting the rings together.

3. In a garment supporter, a fastener including a rectangular oblong shaped clamping ring formed of round wire stock including parallel side bars and connecting cross bars, a second rectangularly shaped clamping ring formed of round wire stock movable relative to the first ring and including parallel side bars and connecting cross bars, said second ring being of a less width than 45 the first ring and of a greater length, whereby the second ring can be inserted through the first ring and overlie the end cross bars thereof for gripping a stocking, and means loosely connecting the rings together.

55 4. In a stocking supporter, a supporting loop, a gripping ring formed of round wire stock of rectangular shape in plan suspended from the supporting loop, a second gripping 60 ring formed of round wire stock of rectangular shape in plan, a fabric tab connected with the second ring and secured to the first ring, said second ring being of a less width than the first ring and of a greater length 65 and insertable through the first ring for

engaging the ends thereof for gripping a stocking therebetween.

5. A fabric grip for general purposes comprising a main open body of rectangular configuration in plan arranged to lie on one side of the fabric to be held and a second clamping body formed of round wire stock of less width and greater length than the main body for initially engaging the other side of the fabric, said second clamping 70 body being insertable with the fabric through the main body for clamping the fabric between the opposite ends of said bodies, and means loosely connecting said bodies together.

In testimony that I claim the foregoing I have hereunto set my hand at Milwaukee, in the county of Milwaukee and State of Wisconsin.
